ABSTRACT

According to the invention, there is provided, in or for a surface treating machine, such as a floor polisher or a hand-held sander, a shield for preventing damage to obstructions adjacent the surface being treated. This shield may consist of a ring of soft material mounted for relative rotation on a rotatable attachment so as to remain stationary if the rotating attachment encounters an obstruction.

ROTARY GUARD FOR SURFACE TREATING MACHINES

This invention relates to surface treating machines of the rotating type, i.e., in which one or more brushes or other attachments rotate about a vertical axis or axes while in contact with a floor or other surface to be treated, e.g. scrubbed, polished, sanded, buffed or otherwise conditioned.

According to the present invention, a brush or other attachment for a floor or other surface treating machine of the rotating type is provided with a shield to prevent contact of the brush or other attachment against wall or other obstructions, the shield being mounted on the supporting back of the brush or other attachment and free to rotate relative thereto so that it can remain stationary in contact with an obstruction while the brush or other attachment continues to rotate.

The invention will be further described with reference to the accompanying drawing, which drawing is a sectional view of part of a brush back incorporating a buffer according to a preferred form of the invention.

The drawing shows part of a brush back 1 of a floor treating machine which is horizontal in use and adapted to rotate about a vertical axis. Bristles of a polishing pad or the like will normally be attached to the lower surface of the brush back 1 so as to be in contact with the floor as the brush back rotates. A backing ring 3, in the form of an aluminum extrusion, is bent round the periphery completely. The backing ring 3 has a lower flange 3a and is securely mounted on the brush back 1.

A securing ring 2 is secured on the upper surface of the brush back by means of screws 2a and projects beyond the backing ring 3. A shield 5, in the form of an extrusion in polyvinylchloride or other plastics material, is formed into a ring and butt jointed and is stretched and/or bonded onto a slip ring 4, which is itself an extrusion of nylon or other anti-friction material also formed into a ring and butt jointed.

The slip ring 4 has two inward extensions 4a which

are in sliding contact with the backing ring 3, and the assembly of buffer and slip ring 4 is retained on the backing ring 3 by the securing ring 2 and the flange 3a.

It will be appreciated that when the brush back 1 is rotating about a vertical axis, the shield 5 will normally rotate with it, but on contact with a wall or other construction such as an article of furniture, the shield will be braked by such contact and the brush back will continue to rotate.

A similar type of shield may be provided on rotary surface treating machines of types other than floor treating machines, such as hand-held sanding or buffing machines, so that obstructions on adjacent surfaces steeply inclined or perpendicular to the surface being treated are not so susceptible to damage by the machine.

It will be seen that the possibility of marking or damaging the wall or furniture or work pieces is very much reduced by provision of the slipping shield.

Various modifications may be made within the scope of the invention.

What is claimed is:

1. A floor or other surface treating machine of the rotary type comprising a rotary brush having a brush back 25 rotatably attached to said machine, said brush back being cylindrical, a shielding means mounted to extend about the periphery of said brush back, said shielding means comprising a backing ring mounted on the periphery of said back with a flange extending radially outward from the lower edge thereof, a slip ring of anti friction material received on and engaging the periphery of the backing ring and being free to rotate relative to the brush back wherein the shielding means may remain stationary against an obstruction or in rolling contact with the obstruction while the brush back continues to rotate at operating speed.

2. An article as claimed in claim 1, in which a ring of elastomer material is mounted in said slip ring.

3. An article as claimed in claim 1, in which the slip ring has extension surfaces in sliding engagement with the backing ring.
